D. Swift Attorney

UNITED STATES PATENT OFFICE.

GROVER C. HOOD, OF DILWORTH, OKLAHOMA.

CLEANING-ROD FOR FIREARMS.

1,325,292.

Specification of Letters Patent. Patented Dec. 16, 1919.

Application filed May 19, 1919. Serial No. 298,298.

To all whom it may concern:

Be it known that I, GROVER C. Hood, a citizen of the United States, residing at Dilworth, in the county of Kay, State of Oklahoma, have invented a new and useful Cleaning-Rod for Firearms; and I do hereby declare the following to be a full, clear, and exact description of the invention, such as will enable others skilled in the art to 10 which it appertains to make and use the same.

The invention relates to cleaning rods for fire arms and has for its object to provide a metallic rod, which rod has its upper 15 end provided with a finger loop whereby the rod may be grasped, and to provide its lower end with a transverse slot, through which slot a rag may be passed to be forced into the bore of a gun for cleaning the same. It 20 is also an object of the invention to provide the end of the rod with a tapering portion terminating in a hook, said hook being adapted to be forced into the rag if the same should become jammed in the bore of 25 the gun, which often happens in cleaning bores of guns by this type of rod, the tapering hooked end being normally, during a cleaning operation, covered by a cap which threads on the end of the rod.

With the above and other objects in view the invention resides, in the combination and arrangement of parts, as hereinafter set forth, shown in the drawings and described and claimed, it being understood that 35 changes in the precise embodiment of the invention may be made within the scope of what is claimed without departing from the spirit of the invention.

In the drawings:—

40 Figure 1 is a side elevation of the cleaning rod.

Fig. 2 is a sectional view through the lower end of the rod.

45 Fig. 3 is a perspective view of the lower end of the rod.

Referring to the drawings, the numeral 1 designates a conventional form of gun cleaning rod, which is preferably formed from heavy brass wire, but may be formed 50 from steel if so desired. The upper end is provided with a loop 2, which loop forms means whereby the rod may be grasped to force the same into the bore of a gun. Extending transversely through the lower end

3 of the rod is a slot 4, this slot 4 being 55 adapted to receive a cleaning rag 5. End 3 of the rod is provided with a threaded reduced portion 6, from the lower end of which extends a tapered member 7, which tapered member terminates in a sharp point 60 8, there being a hook 9 spaced from the end 8. Telescopically fitting over the tapered portion 7 is a metallic cap 10, the open end of which is provided with threads 11 which are adapted to be received by the threads 65 on the threaded portion 6.

When it is desired to clean the bore of a gun, a rag 5 is passed through the transverse slot 4 then the lower end of the rod is forced into the muzzle of the gun and the 70 rag will be carried into the same. After the rag is well within the muzzle of the gun a reciprocating movement is imparted to the cleaning rod, thereby causing the rag 5 to clean and burnish the bore of the 75 gun. However, during this reciprocating motion, it sometimes happens that the rag will come out of the transverse opening 4 and become jammed in the bore of the gun. When this happens the cover 10 is removed 80 from the end of the rod, then the tapered portion is forced downwardly into the rag until the hook 9 has passed therethrough; after the hook 9 assumes this position a pull is imparted on the rod which will cause the 85 hook 9 to engage the rag and pull the same out of the bore of the gun. When the rag has been removed the cap 10 is again placed on the end of the cleaning rod.

The invention having been set forth what 90 is claimed as new and useful is:—

1. A gun cleaning rod comprising a body portion, said body portion being provided with a tapering pointed end, said end having a hook spaced from the point thereof, a 95 threaded cap threaded on the end of said rod and telescopically fitting over the tapered end thereof and a transversely disposed slot extending through said body portion adjacent the upper end of said threaded 100 cap member.

2. A gun cleaning rod comprising a body portion, said body portion being provided with a transverse slot near its lower end, a reduced threaded portion adjacent said 105 transverse slot, said reduced threaded portion having a downwardly extending tapered portion terminating in a sharp point,

said tapered portion having a hook spaced from the point thereof, a cap telescopically fitting over the tapered portion and having its open end provided with threads adapted 5 to be received by the threaded reduced portion.

In testimony whereof I have signed my

name to this specification in the presence of two subscribing witnesses.

GROVER C. HOOD.
